RECEPTACLE FOR NEWSPAPERS AND
THE LIKE**Harry E. Curtis, Willoughby, and Glenn L. Egbert,
Cleveland, Ohio**

Application April 12, 1952, Serial No. 19,303

Term of patent 14 years

(Cl. D33—2)

To all whom it may concern:

Be it known that we, Harry E. Curtis, a citizen of the United States, residing at 34007 Lakeshore Boulevard, Willoughby, Ohio, and Glenn L. Egbert, a citizen of the United States, residing at 4021 Lancaster Road, Cleveland, Ohio, have invented a new, original, and ornamental Design for a Receptacle for Newspapers and the like, of which the following is a specification, reference being had to the accompanying drawing, forming a part hereof.

In the drawing:

Fig. 1 is a perspective view of a receptacle for newspapers and the like, showing our new design;

Fig. 2 is a front elevational view thereof; the rear elevation being substantially the same;

Fig. 3 is a sectional view thereof taken substan-

tially on the line 3—3 of Fig. 1 and looking in the direction of the arrows; and

Fig. 4 is a top plan view thereof.

We claim:

The ornamental design for a receptacle for newspapers and the like, substantially as shown and described.

HARRY E. CURTIS.
GLENN L. EGBERT.
